Primary Examiner — Leanne Was-Englehart

(74) *Attorney, Agent, or Firm* — Quarles & Brady LLP

CLAIM

The ornamental design for a fence, as shown and described.

DESCRIPTION

The sole FIGURE is a perspective view of a front, top, and left side of a fence, the perspective view of the rear, top, and left side being a mirror image thereof.

The broken lines are included for the purpose of illustrating portions that form no part of the claimed design.

1 Claim, 1 Drawing Sheet
